CAR REPLACER

William B. Boone, Florence, S. C.

Application January 26, 1938, Serial No. 187,052

3 Claims. (Cl. 104—265)

The invention relates to car replacers and more particularly to railway rolling stock rerailers.

The primary object of the invention is the provision of a device of this character, wherein the same is adaptable for clamping to a rail of railway trackage either inside or outside of said rail so that the locomotive or a freight or passenger car can be readily rolled onto the track when becoming derailed without liability of damaging the flanges of the wheels during rerailing of the same, the device being of novel construction to assure replacing of the locomotive or car upon the track with dispatch.

Another object of the invention is the provision of a device of this character, wherein the same is susceptible of being conveniently fixed in position and held firmly in such position to avoid displacement when in use for rerailing purposes of rolling stock upon the rails of a track.

A further object of the invention is the provision of a device of this character, which is simple in its construction, thoroughly reliable and efficient in operation, portable, easy of application and removal to trackage, strong, durable, and inexpensive to manufacture.

With these and other objects in view, the invention consists in the features of construction, combination and arrangement of parts as will be hereinafter more fully described, illustrated in the accompanying drawings, which disclose the preferred and modified forms of embodiment of the invention and pointed out in the claims hereunto appended.

In the accompanying drawings:

Figure 1 is a fragmentary plan view of the rail of a railway track showing a car replacer constructed in accordance with the invention in association therewith.

Figure 2 is a side elevation with the clamp partly in section.

Figure 3 is a vertical transverse sectional view through the rail showing the car replacer in end elevation and associated therewith.

Figure 4 is a vertical transverse sectional view through the car replacer.

Figure 5 is a view similar to Figure 1 showing a modified form of replacer preferably for use at the inside of a track.

Figure 6 is a side elevation partly in section thereof.

Figure 7 is an end elevation of the same.

Figure 8 is a vertical transverse sectional view therethrough.

Similar reference characters indicate corre-

sponding parts throughout the several views in the drawings.

Referring to the drawings in detail, A designates generally a portion of a track rail and B a portion of a railway car wheel or locomotive wheel, respectively, these being conventional and as usual the rail is a part of a track supported upon cross ties, a portion of one of the same being indicated at 10, these being illustrated merely to show the application and the use of the car replacer constituting the present invention and hereinafter fully described.

In Figures 1 to 4 inclusive of the drawings there is illustrated a car replacer generally indicated at C for use at the outer side of the rail A when replacing or rerailing a car upon the track and includes an elongated body 11 cast or otherwise formed from metal having built therewith at one longer edge a vertically disposed abutting wall 12 of a height and in formation for interfitting with the rail A between its ball and base for abutment with the vertical web of said rail. The top or upper surface of the body 11 has formed thereon successively arranged risers or steps 13, 14 and 15, respectively, increasing in height with respect to each other laterally in an outward direction from the wall 12, and said steps or risers slope reversely to each other toward opposite ends of the body from a transverse median area 16 in a longitudinal direction of said body. The reversely sloping extent of the steps or risers converge toward the wall 12 and merge into the median area 16 to present guide shoulders 17 and 18, respectively, at the top or upper side of the body 11 for directing the rail flange 19 and the wheel B bearing the same onto the rail A when rolling upon the reverse slopes incident to the steps 13, 14 and 15.

The step 15 at the area 16 has the shoulder 18 common thereto in continuity with a substantially V-shaped deflector nose 20 confronting a depression 21 next thereto and created in the steps 13 and 14 to be next to the rail or the wall 12 of said body while at the merger points of the said steps 13 and 14 with the depression 21 are upwardly arched bulges 22 which are at a height above the plane of the tread face of the ball of the rail A so that the flange 19 of the wheel B will clear this tread of the said ball of the rail when the wheel is rerailed or replaced by the shoulders 17 and 18 from outside of the track having said rail in the use of the said body 11 when placed at the outer side of the track and anchored by suitable spikes 23. These spikes 23 are passed through suitable holes in an anchoring 55

flange 24 formed on the body 11. The body 11 is clamped firmly to the rail A through the use of a clamping hook 25, its shank being passed through a receiving slot or opening 26 provided 5 in the outside vertical wall 27 of said body 11, the latter being hollowed at 28 inwardly from the bottom side thereof. The shank 29 of the hook 25 accommodates in a clearance 30 a retaining key 31 and in this manner the hook 25 is 10 fastened in the body 11 in hooking engagement with the rail A and thus clamping the body 11 firmly to the rail.

The wheels B ride onto the steps at the top or upper face of the body 11 from either end of 15 the latter, these being the entrance ends of said body for the wheels of a railway car or locomotive.

In Figures 5 to 8 inclusive of the drawings there is shown a modified form of car replacer or rerailler D, being a companion to the replacer 20 or rerailler C hereinbefore described, and is adaptable for placement of the car wheels onto the rail A when these wheels are derailed and are disposed between the said rails of the track or within the latter.

25 The replacer D includes a body 32 having the vertical abutting wall 33 at one longer side thereof which is engaged with the rail A at the inner side of the same between the ball and base and held against the vertical web of said rail while 30 the top of this body 32 has the spaced steps or risers 34 and 35, respectively, these being next to the opposite longer edges of said body and are reversely sloped in the direction of the opposite ends of the body on opposite sides of a transverse median area 36 of said body where there exists a hollow or depression 37 and a deflector nose 38, respectively, these being in confronting relation with the hollow or depression 37 next to the rail A. The steps 34 and 35 through the formation 40 of guideways 39 and 40, respectively, present guide shoulders 41 and 42, respectively, to said steps, these opening into the depression 37 to merge thereinto, the ways 39 being substantially parallel with the rail A and at the outer ends 45 thereof come flush with the step 34 while the ways 40 inwardly converge in the direction of the rail A and meet the nose 38 while the said ways at their outer ends open through opposite ends of the body 32. The body 32 is clamped to the rail A similarly to the body 11 and also is fixed to a cross tie corresponding to the fixing of the said body 11. These replacers C and D, companions when in use for replacing or rerailing 50 a car upon a track, will assure the passing of the wheels both within the track and outside of the same onto the rails thereof without damaging the flanges of the wheels and the replacing or rerailing is had in two directions by the rolling

of the wheels onto the bodies 11 and 32 from either end thereof.

What is claimed is:

1. In a replacer of the kind described, a pair 5 of elongated block-like bodies for disposition, one at the inside of a track rail and the other at the outside of the said rail, each formed with a raised medial portion and reversely sloping portions at opposite sides thereof, steps in successive elevation relative to each other including treads 10 and risers formed on said portions and converging toward a rail next to the side of one of said bodies and gradually diminishing in the direction of the said medial portion, a concaved area formed in certain of said steps and located at 15 the medial portion inwardly to the remaining step, and a deflector nose formed at the remaining step and within the medial portion and directed toward the concaved area.

2. In a replacer of the kind described, a pair 20 of elongated block-like bodies for disposition, one at the inside of a track rail and the other at the outside of the said rail, each formed with a raised medial portion and reversely sloping portions at opposite sides thereof, steps in successive 25 elevation relative to each other including treads and risers formed on said portions and converging toward a rail next to the side of one of said bodies and gradually diminishing in the direction of the said medial portion, a concaved area 30 formed in certain of said steps and located at the medial portion inwardly to the remaining step, a deflector nose formed at the remaining step and within the medial portion and directed toward the concaved area, and guide shoulders 35 present with said steps on one body and gradually increasing in size vertically in upward convergent relation to each other.

3. In a replacer of the kind described, a pair 40 of elongated block-like bodies for disposition, one at the inside of a track rail and the other at the outside of the said rail, each formed with a raised medial portion and reversely sloping portions at opposite sides thereof, steps in successive elevation relative to each other including treads 45 and risers formed on said portions and converging toward a rail next to the side of one of said bodies and gradually diminishing in the direction of the said medial portion, a concaved area formed in certain of said steps and located at 50 the medial portion inwardly to the remaining step, a deflector nose formed at the remaining step and within the medial portion and directed toward the concaved area, guide shoulders present with said steps on one body and gradually increasing in size vertically in upward convergent relation to each other, and a clamp for fastening each body associated with the rail.

WILLIAM B. BOONE.
